TRACTOR SEAT

Donald G. Zank and Norman J. Harvey,
Bellevue, Nebr.

Application December 13, 1949, Serial No. 6,582

Term of patent 14 years

(Cl. D15—8)

To all whom it may concern:

Be it known that we, Donald G. Zank and Norman J. Harvey, citizens of the United States, residing at Bellevue, in the county of Sarpy and State of Nebraska, have invented a new, original, and ornamental Design for Tractor Seat, of which the following is a specification, reference being had to the accompanying drawing, forming part thereof.

Figure 1 is a front and side perspective view of a tractor seat, showing our new design.

Figure 2 is a perspective view of the rear of the tractor seat.

Figure 3 is a bottom plan view showing the same.

The seat is made of foraminous material allowing the outline of certain portions to be seen through said seat in all three views.

We claim:

The ornamental design for a tractor seat, as shown and described.

DONALD G. ZANK.
NORMAN J. HARVEY.
